UNITED STATES PATENT OFFICE.

NOBLE S. CLAY, OF WILKINSBURG, PENNSYLVANIA, ASSIGNOR TO WESTINGHOUSE ELECTRIC & MANUFACTURING COMPANY, A CORPORATION OF PENNSYLVANIA.

TIP FOR PROPELLERS.

Application filed October 27, 1920. Serial No. 418,812.

My invention relates to propellers, and more especially to propellers employed in the propulsion of airplanes.

Airplane propellers are subject to destructive influence, such as contact with plant growth, rain, or spray, with the consequent result that the ends and leading edges are speedily damaged and destroyed. To lengthen the life of such propellers, it has been proposed to provide metal tips on the ends thereof, such tips being mounted thereon by screws or rivets, or deposited by electrolysis, but it was found that the vibration and slight bending of the propeller blades caused cracking and destruction of the tips and propeller ends.

In the application of tips to propeller blades, it is desirable to replace worn parts, and it is among the objects of my invention to provide tips for the leading edges of propellers which have a hard, wear-resistant surface, yet are flexible, so that slight bending or vibration of the propeller blades will not crack them and which may be readily replaced.

It is another object of my invention to provide composite propellers for naval or other use with non-corrosive molded or metal tips.

It is a further object of my invention to provide propellers with durable tips molded to the propeller body.

In practicing my invention, I provide means for securing tips to propeller blades in such manner as to prevent the formation of cracks in, or other damage to, the body portion. I may utilize preformed or molded tips of the desired shape embodying a binder such as a phenolic condensation product, and a fibrous filler, preferably a duck material. The tips may be molded to correct shapes for mounting and suitable openings may be formed therein for the insertion of screws or rivets. For severe service, a small percentage of powdered silica may be added to the molding composition or may be sprinkled on the surfaces of the material before the final molding, thereby producing a very hard, wear-resisting surface on the tips. In the case of composite propellers, I may mold metal tips into the body portion or secure them to metal inserts molded into the mi-

In the accompanying drawings, forming a part hereof, and in which similar reference characters denote similar parts,

Fig. 1 is an elevational view of a propeller having detachable tips;

Fig. 2 is an enlarged view of one of the tips shown in Fig. 1; and

Fig. 3 is an elevational view of an end portion of a composite or wood propeller showing metal inserts molded into or formed on the propeller blade and adapted to hold a molded or metal tip in position.

Referring to Figs. 1 and 2, a propeller body 1 may have tips 2 secured thereto by screws or rivets 3 having countersunk heads to avoid projections on the surface of the propeller. In the embodiment shown in Figs. 1 and 2, the metal tip 2 is molded to the body portion 1 and may be further secured by screws 3, if so desired.

In the form shown in Fig. 3, metal strips or inserts 4 are molded into the body 1 of the propeller and the molded or metal tips 2 are secured thereto by screws or rivets 3.

An example of the application of my invention is as follows:

Layers of duck impregnated with a soluble, fusible phenolic condensation product and cut to the proper shapes, are built up to form a propeller body. Metal strips or inserts 4 are fitted between layers on the propeller ends at or near the surface thereof and the whole structure is subjected to heat and pressure in a mold to render the mass insoluble and hard. Metal tips 2 formed to the desired shape are secured to the inserts 4 by means of screws or rivets 3.

This structure has several advantages in that the metal tips are more securely fastened to the propeller ends, thus eliminating the danger of their becoming loose or cracking. This construction also allows tips which have become damaged to be removed by simply removing the screws which hold them in place and then securing new tips in their stead.

Although I have shown and described specific embodiments of my invention, it is to be understood that my invention is not limited to the exact structure herein set forth as various changes can be made in details of construction without departing from the principles thereof. For instance,

metal or molded tips may be secured to metal inserts in wooden propellers, the inserts being fitted between plies of wood and the tips secured thereto by suitable screws or rivets. Metal tips may be molded directly on the composite propeller, or tips of composite material may be molded to wooden or composite propellers. It is obvious that a molding composition other than a phenolic condensation product and fibrous material may be used.

Although I prefer to form my molded tip with silicious material incorporated therein, I may omit such material or substitute therefor other hard, wear-resisting materials such as emery, corundum, carborundum, and the like.

I claim as my invention:

1. A propeller comprising a body portion, inserts molded in the ends thereof, tips mounted on said ends, and means for securing said tips to said inserts.
2. A propeller comprising a body portion of fibrous material and a phenolic condensation product, inserts molded in the ends thereof, premolded tips mounted on said

ends, and means for securing said tips to said inserts.

3. A propeller comprising a body portion, and molded tips on the ends thereof, said tips comprising a phenolic condensation product and wear-resisting material.

4. A propeller comprising a body portion, and tips comprising a wear-resisting molding mixture, said tips being molded on the ends of said body portion.

5. A molded propeller comprising fibrous material and a phenolic condensation product, inserts molded in the ends thereof, premolded tips on said ends and means to secure said tips to said inserts.

6. A molded propeller of fibrous material and a phenolic condensation product, inserts molded in the ends thereof, premolded tips comprising a wear-resisting material and a phenolic condensation product on said ends and means for securing said tips to said inserts.

In testimony whereof, I have hereunto subscribed my name this 14th day of October, 1920.

NOBLE S. CLAY.
